Marshall R. Scott, Ripon, Wis., assignor to Bar-
low & Seelig Mfg. Co., Ripon, Wis., a corpora-
tion of Wisconsin

Application April 25, 1935, Serial No. 56,558

Term of patent 14 years

To all whom it may concern:

Be it known that I, Marshall R. Scott, a citizen of the United States, residing at Ripon, in the county of Fond du Lac and State of Wisconsin, have invented a new, original, and ornamental Design for a Leg for a Washing Machine or Similar Article, of which the following is a specification, reference being had to the accompanying drawing, forming part thereof.

The figure is a perspective view of a leg for a washing machine or similar article showing my new design.

I claim:

The ornamental design for a leg for a washing machine or similar article substantially as shown.

MARSHALL R. SCOTT.
